O. L. WALLACE

SHORE

Filed May 19, 1923

FIG. 1.

FIG. 2.

O. L. WALLACE INVENTOR
by *Victor J. Evans*

ATTORNEY

WITNESS:

UNITED STATES PATENT OFFICE.

OSCAR L. WALLACE, OF PITTSBURGH, PENNSYLVANIA.

SHORE.

Application filed May 19, 1923. Serial No. 640,252.

To all whom it may concern:

Be it known that I, OSCAR L. WALLACE, a citizen of the United States, residing at Pittsburgh, in the county of Allegheny and State of Pennsylvania, have invented new and useful Improvements in Shores, of which the following is a specification.

This invention relates to shores for use in building construction.

One of the main objects of the invention is to provide a shore which may be readily adjusted and the parts of which may be quickly and easily but effectually secured in adjusted relation. This invention is intended more particularly as an improvement and simplification of the shore disclosed in my U. S. Patent 1,400,109, the primary object of the present invention being to simplify the shore disclosed in my patent referred to and to produce a shore which may be quickly and easily adjusted while being of very simple and efficient construction. Further objects will appear from the detailed description.

In the drawings:—

Figure 1 is a front view of the lower keeper and associated parts;

Figure 2 is a section taken substantially on line 2—2 of Fig. 1;

Figure 3 is a front view of the shore;

Figure 4 is a side view;

Figure 5 is a back view.

The shore includes an upright 1 which is preferably formed of a suitable length of angle iron. A post 2 which may be formed from a suitable length of three-by-four studding or timber is slidably mounted in upright 1. This post slides through a lower U-shaped keeper 3 and an upper U-shaped keeper 4. The lower keeper 3 is inclined downwardly and forwardly of the shore and is pivoted on gudgeons 5 which project from the ends of a block 6 extending across the back of upright 1, nuts 7 being threaded onto the gudgeons to prevent spreading apart of the arms of keeper 3. Block 6 is provided on its inner face with a stud 8 which is adapted to fit into any one, selectively, of a plurality of openings 9 provided for this purpose through rear arm 1^a of upright 1. A wedge 10 is driven between the bight portion of lower keeper 3 and the lower portion of post 2 which has its lower

end portion beveled to provide an inclined surface 2^a. Upper keeper 4 is pivoted on a pin 11 which passes through a sleeve 12 of a plate 13 riveted at 14 on arm 1^a of post 1, nuts 15 being threaded on the ends of pin 11. This upper keeper 4 is also inclined downwardly and forwardly of upright 1 and a wedge 16 is driven between the bight portion of keeper 4 and post 2. This provides simple and efficient means whereby the post is effectually secured in adjustment.

In using the shore, the lower end of post 1 is placed upon a suitable supporting member or plate *a* after which a suitable jack *A* is supported in position upon the upright with the head of the jack in contact with the lower end of post 2. The jack may be supported in any suitable or preferred manner though I prefer to use a hook *b* which is secured to the jack and is adapted to engage through any one, selectively, of the openings 9, as clearly illustrated and described in my patent above identified. Post 2 is raised into position by means of jack *A*, after which keeper 3 is adjusted and the wedges 10 and 16 are driven in position. The block 6 and stud 8 effectually secure keeper 3 against downward movement while permitting this keeper to be readily adjusted when wedge 10 is removed or loosened during adjustment of post 2. By this means I provide a very simple and efficient device which may be quickly and easily adjusted and in which the post is effectually secured in adjusted position. While I have described and illustrated the use of an angle iron for standard 1 I can, if desired, use a suitable piece of timber, such as a three-by-four studding, which is provided in its rearward face with recesses for reception of stud 8, post 2 being slidably mounted and secured in adjustment by means of the keepers 3 and 4 and associated parts in the manner described.

What I claim is:—

In a shore, an upright, a post slidably mounted on the upright, means at the upper end of the upright for preventing outward movement of the post away from the upright, a block extending across the rearward face of the upright and provided with an inwardly projecting stud, the upright having a vertical series of openings for reception of said stud whereby the block is ad-

justably mounted on said upright and positively secured in adjustment thereon, the lower end portion of the post being beveled downwardly and inwardly of the upright, 5 a keeper pivoted to the ends of the block and extending across and in front of the beveled portion of the post, and a wedge driven be-

tween the bight portion of the keeper and the beveled portion of the post and coacting with the keeper for effecting upward adjustment of the post and for securing the post in adjustment. 10

In testimony whereof I affix my signature.

OSCAR L. WALLACE.
